Primary Examiner — Ramzi S Almatrahi

(74) Attorney, Agent, or Firm — Haynes and Boone, LLP

(57) **CLAIM**

The ornamental design for a camera, as shown and described.

DESCRIPTION

FIG. 1 is a front, left, and top perspective view of a camera showing the new design illustrated in a first orientation; FIG. 2 is a front elevational view thereof; FIG. 3 is a rear elevational view thereof; FIG. 4 is a right side view thereof; FIG. 5 is a left side view thereof; FIG. 6 is a top plan view thereof; FIG. 7 is a bottom plan view thereof; and FIG. 8 is a rear, right, and bottom perspective view thereof. FIG. 9 is a rear, left, and top perspective view of the camera illustrated in a second orientation, wherein a first portion of the camera (e.g., a lens assembly), may be selectively moved to one or more positions relative to a second portion of the camera (e.g., an interactive user interface); FIG. 10 is a front elevational view thereof; FIG. 11 is a rear elevational view thereof; FIG. 12 is a right side view thereof; FIG. 13 is a left side view thereof; FIG. 14 is a top plan view thereof; FIG. 15 is a bottom plan view thereof; and, FIG. 16 is a front, right, and bottom side elevational view thereof. The broken lines depict portions of the camera in which the design is embodied that form no part of the claimed design.

1 Claim, 14 Drawing Sheets
